UNITED STATES PATENT OFFICE.

MATTHEW BROWN WILD, OF BIRMINGHAM, ENGLAND.

WINCH.

1,281,732.

Specification of Letters Patent. Patented Oct. 15, 1918.

Application filed July 26, 1917. Serial No. 182,884.

To all whom it may concern:

Be it known that I, MATTHEW BROWN WILD, a subject of the King of Great Britain and Ireland, residing at 37 Arthur road, 5 Erdington, in the city of Birmingham, England, have invented certain new and useful Improvements Relating to Winches, of which the following is a specification.

This invention relates to winches for use 10 on ship-board and for other services, and particularly of the type employed for the loading and unloading of a vessel's cargo and having a plurality of drums or barrels driven from an electric or other motor con- 15 stantly running in the one direction.

The invention comprises improved means as hereinafter described for transmitting the power from the motor to the respective 20 winch barrels and for the control of the latter during the lifting and lowering operations.

Referring to the four accompanying sheets of explanatory drawings:—

Figure 1 is a side elevation, Fig. 2 a plan, 25 and Fig. 3 an end elevation (to a larger scale), illustrating a double barreled electric winch constructed in accordance with this invention.

Figs. 4 to 11 are views showing various 30 details of the machine as follows:—

Fig. 4 is an elevation, partly in section, of one of the barrels and its epicyclic gear train.

Fig. 5 is an end elevation and Fig. 6 a sectional side elevation of a brake rim with the 35 automatic speed control device.

Fig. 7 is an end elevation of a brake rim fitted with hand or manual brake.

Fig. 8 is an end elevation and Fig. 9 a side 40 elevation of the composite brake band, while

Fig. 10 is a plan representing (to a smaller scale) the said band extended in straight line form.

Fig. 11 is a side elevation showing a portion 45 of a detachable brake rim.

The same reference letters in the different views indicate the same or similar parts.

In one convenient construction and arrangement of a multi-barreled electric winch 50 in accordance with this invention, the armature shaft of the motor *a* is fitted with a worm adapted to drive a worm wheel secured to the center of a barrel shaft *b* extending throughout the bed-plate of the 55 winch and having one, two, or more barrels as *c* thereon. From such shaft one or more

additional shafts may be driven through clutch controlled gear wheels, each of such additional shafts being fitted with barrels, warping drums or the like as may be required. 60

The barrels *c*, mounted loosely on their shaft *b* are each driven through an epicyclic gear train, preferably comprising (as shown at Fig. 4) a sun wheel or pinion *d* secured to 65 and therefore rotating with shaft *b* and having adjacent thereto and concentric therewith another sun wheel *e* loose with respect to the said shaft *b* but fixed to a brake or retaining disk or wheel *f*. The said sun 70 wheels *d* and *e* respectively engage planetary pinions *g* and *h* integrally mounted on pins or axes fixed to the adjacent ends of the barrel *c* and a planet carrier *i*. The whole of the gear train is inclosed by the 75 brake rim *j* at the adjacent end of the barrel *c* and the rim of the planet carrier *i*, the said rims being bolted or otherwise connected to form an oil box or bath totally inclosing the gearing. 80

At the opposite end of the barrel there is provided, within the rim *k* at the said end, an automatic clutch to form the control connection between the barrel *c* and the driving shaft *a* during the lowering movement of 85 the barrel while the epicyclic gear train aforesaid is inactive. In the form shown at Figs. 5 and 6 the said clutch comprises a brake band as *l* contacting with the periphery of a disk *m* keyed to the driving or barrel shaft *b* and brought into service by centrifugal force acting on the interconnected weighted levers *n* carried within the rim *k*. Regulation to the desired speed limit is effected by adjustment of the retaining 90 springs *o*.

For the lifting movement or rotation of the barrel the aforesaid retaining disk or wheel *f* and the sun wheel *e* fixed thereto are held against rotation by means of a 100 brake band *l* embracing the rim of the disk and actuated by the hand lever *p*. By the rotation of the driving shaft *b* the planet wheels *g* and *h* are then caused to travel around the sun wheels *d* and *e* thus rotating 105 the barrel *c* and so lifting the load by the coiling of the rope upon the barrel.

For lowering the retaining disk *f* and its sun wheel *e* are released, thus permitting the load in descending to reverse the rotation of 110 the barrel *c* with the driving shaft *b* still running in its normal direction. The de-

- scent of the load is controlled by brake straps or their equivalent acting upon the rim *j* and *k* at the ends of the barrel. Excessive speed in lowering is prevented by the 5 automatic clutch, hereinbefore described, within the rim *k* forming the control connection between the barrel and the driving shaft. By such control connection an excess rate of rotation, or the tendency to such 10 excess, results in the motor *a* being operated as a generator of electrical energy thus providing an automatic limitation of the speed of lowering. Control of the lowering within the speed limit is effected by a brake 15 band embracing the rim *j* and actuated by the foot lever *q*. Such foot lever may actuate two brake bands, one embracing the rim *j* as aforesaid and the other the rim *k* at the opposite end of the barrel.
- 20 The brakes for the barrel rims *j* and *k* and also for the retaining disk *f* of the wheel *e*, preferably comprise a steel band, lined with suitable fibrous or other friction creating material, which is made to form a 25 circle to completely embrace the periphery of the rim. The greater length or portion of the band is made up of two steel strips as *l*¹ and *l*² (Figs. 9 and 10) of such width as to give a lateral cooling space *l*³ between 30 them on the brake rim. To complete the ring or annulus for entirely embracing the rim the said pair of strips are at one end connected preferably by a plate *l*⁴ to a shorter strip *l*⁵ adapted to pass through the 35 lateral space aforesaid. One end of the band is connected to a hand or foot control lever and the opposite end to a fixed anchorage as *l*⁶ (Fig. 8).
- The brake rims *j* and *k* of the barrel *e* can 40 be made separate from the ends or flanges of the same in the same manner that, as illustrated at Figs. 4 and 7, the rim of the sun wheel retaining disk *f* is made separate therefrom. Such separate rim is fixed in

position by bolts and nuts as *r* or in any convenient manner such as will provide an air space on the underside for cooling purposes. The cooling effect is much enhanced by arranging fan like ribs or vanes as *s* in the 45 said air space. 50

Having thus described my invention what I claim as new and desire to secure by Letters Patent is:—

1. In winches, the combination consisting of a barrel, a brake rim at each end of said barrel, a shaft having the said barrel mounted loosely thereon, means for driving the said shaft, a manual brake for the rim at one end of the barrel, an automatic brake for the rim at the opposite end of the barrel, an 55 epicyclic gear train between the shaft and the barrel, a brake disk controlling the said gear train, and an oil box totally inclosing the gear train, as set forth. 60

2. In winches, the combination consisting of a barrel, a brake rim on said barrel, a multiple strip brake band forming a complete circle embracing the said brake rim, a cooling space between the said brake band strips, a shaft having the said barrel mounted loosely thereon, means for driving said 70 shaft, an epicyclic gear train between the shaft and the barrel, a brake disk controlling said gear train, and an oil box totally inclosing the gear train, as set forth. 75

3. In winches, the combination consisting of a barrel, a brake rim in separable connection with said barrel, an air space between the said rim and the barrel, fan vanes in the said air space, a shaft having the barrel mounted loosely thereon, means for driving said shaft, an epicyclic gear train between the shaft and the barrel, a brake disk controlling said gear train, and an oil box totally 80 inclosing the gear train, as set forth. 85

In testimony whereof I have signed my name to this specification.

MATTHEW BROWN WILD.
